UNITED STATES PATENT OFFICE.

CHRISTIAN F. HEINKEL AND JOHN MUTH, OF CLEVELAND, OHIO; SAID MUTH
ASSIGNOR TO SAID HEINKEL.

DRILL.

1,022,135.

Specification of Letters Patent.

Patented Apr. 2, 1912.

Application filed October 24, 1908. Serial No. 459,381.

To all whom it may concern:

Be it known that we, CHRISTIAN F. HEINKEL and JOHN MUTH, citizens of the United States, residing at Cleveland, in the 5 county of Cuyahoga and State of Ohio, have invented a new and useful Improvement in Drills, of which the following is a specification.

Our invention relates to drills in which 10 one or more cutters are molecularly united to a body.

The object of our invention is to produce a drill which does not break easily and which is economical of manufacture.

15 We attain our object by molecularly uniting one or more cutters of suitable material to a body of softer and more flexible and cheaper material.

It is well known in the art that drills, as 20 heretofore made, are easily broken, particularly the high-speed drills and, being made of higher-priced material throughout, are more expensive of manufacture than the drills of our invention. With our invention, 25 the cutters only are made of higher-priced material while the body is made of softer and cheaper material, thereby reducing cost of manufacture and mitigating breakage.

Our invention is sufficiently illustrated in 30 the accompanying drawing in which:

Figure I is a general side-view of a twist-drill with one cutter and lubrication-tubes. Fig. II is a section on line X—X of Fig. I, showing location of cutter. Fig. III is also 35 a section on line X—X of Fig. I but without cutter and showing the slit. Fig. IV is a general side-view of a straight-fluted drill with a plurality of cutters. Fig. V is a section on line Y—Y of Fig. IV, showing 40 cutters in place. Fig. VI is a modification of Fig. V, showing the narrow cutters partially sunk into the body. Fig. VII is a general side-view of a twist-drill on a smaller scale, showing the cutter extending 45 part way along the body. Fig. VIII is a general side-view of a twist-drill, on a smaller scale and showing an increasing twist.

Similar reference-characters refer to similar parts throughout the several views.

Figs. I, II, and III of said drawing represent a twist-drill which is composed, principally, of a body 1 and a cutter 2.

In carrying out our invention we prefer to construct body 1 of a rather soft and flexible material, such as machinery-steel, wrought-iron, steel casting, malleable-iron, bronze, brass, or even cast-iron if not too brittle, and provide on said body a suitable shank 3. When body 1 is made of 55 commercial bar stock, we prefer to cut the spiral flutes 4 into body 1 by the usual milling operation, which operation also produces slit 5 automatically since no material is left there after flutes 4 are cut; 60 a section of a body with flutes so cut will appear as Fig. III. For the purpose of strength of the twist-drill shown, the faces 8 of spiral flutes 4 are made straight. The leading faces 9 of spiral flutes 4 should be 65 made straight so that cutter 2 may be united thereto readily. Further details for flutes 70 4 will appear hereinafter in connection with description of cutter 2. Grooves 6 may be cut into body 1 and lubrication-tubes 7 may 75 be secured therein by soldering or other suitable means.

Cutter 2 is, preferably, made of high-speed steel, but may be made of a material suitable for general or special work. It will 80 be seen (Fig. II) that cutter 2 extends across the diameter of the drill and fills slit 5 and lies against faces 9. When cutting flutes 4, faces 9 are cut sufficiently deep so that cutter 2 can lie snugly against faces 9 as is 85 clearly shown in Fig. II. For the purpose of providing the proper cutting angle on the drill, cutter 2 is twisted by means of dies, rolls or other similar means well known in the art. Said twist may be a constant twist 90 as seen in Figs. I and VII, or an increasing twist as seen in Fig. VIII; these different twists being well known in the art. The spiral or twist of flutes 4, hereinbefore described, should conform to the twist of cutter 2 so that cutter 2 lies snugly against faces 9, crosswise (Fig. II) as well as lengthwise (Fig. I). For the purpose of 95 grinding or otherwise finally finishing the drill to size, we prefer to first form cutter 2 somewhat wider than the diameter to which the drill is to be finished. Cutter 2 may be hardened before or after molecular union with body 1.

In some methods of molecular union, as 105 for instance in brazing or casting, the har-

dening of cutter 2 and molecular union of body 1 and cutter 2 may be accomplished at one operation and with one heating, as will appear hereinafter.

5 After cutter 2 is properly prepared it is inserted into slit 5 and molecularly united to leading faces 9 of flutes 4. Said molecular union may be accomplished by means of soldering, brazing, welding, casting, or a 10 combination of said means. All of said methods of molecular union, as well as others, are well known in the art and may be employed with suitable modifications; no detailed description thereof is thought necessary here. It may be well to state here, however, that, when casting body 1 to cutter 2, we prefer to apply a suitable binder or flux, such as spelter which is adapted to be fused by the molten material, so that a good 15 joint is obtained on casting.

When producing a drill by means of casting, particularly the larger drills, we prefer to cast flutes 4 into body 1, thus cheapening production or manufacture. In such case, 20 cutter 2 is placed in a suitable mold similar to a core in an ordinary casting and the molten body-material is then poured into said mold. When casting body 1 to cutter 2, we, generally, prefer to place cutter 2 into a 25 suitable mold before said cutter is hardened and, after pouring the molten body-material into said mold, leave the drill in said mold sufficiently long to absorb sufficient heat from said molten material for proper hardening of 30 cutter 2. The drill is then removed from said mold and cooled by a suitable cooling-means whereby said cutter is suitably hardened. Cutter 2 may also be hardened before 35 being placed into said mold and a chill placed over said cutter to prevent annealing. When casting body 1 to cutter 2 of small 40 drills, we, generally, prefer to harden said cutter before the casting operation since the molten material in such small body may not contain sufficient heat to properly heat said 45 cutter for hardening; a chill may or may not be used in such case. When casting body 1 to cutter 2 of a small drill and when 50 said cutter is made of high-speed steel, we prefer to harden said cutter before the casting operation and employ a chill if necessary to prevent annealing of cutter 2. When, however, said cutter is made of carbon 55 steel and the molten body-material contains sufficient heat to harden said cutter, we prefer to harden said cutter by means of the heat from the molten material as hereinbefore described and draw the temper on said cutter by another operation; when the 60 molten body-material contains insufficient heat for hardening of said carbon steel cutter, we prefer to harden said cutter before the casting operation and draw the temper on said cutter either before said casting operation, or during said casting operation by 65

means of the heat of the molten material, or after said casting operation by another heating operation. The material in the body of a larger drill generally, imparts sufficient heat to the cutter for proper hardening so that casting of body and hardening of cutter may be accomplished at one operation and without any additional heating, thus reducing cost of manufacture. The procedure best adapted to any particular case must be 70 judged by the quantity of molten body-material and any one skilled in the art should be able to select the proper procedure from the general descriptions given herein.

When cutter 2 is united to body 1 by 80 means other than casting, brazing for instance, cutter 2 becomes heated and may be heated sufficiently for hardening, thus uniting body 1 and cutter 2 and hardening cutter 2 with one heating and reducing cost of 85 manufacture. After body 1 and cutter 2 are united, cutter 2 is hardened if it was not hardened previous to, or during uniting to body 1. The drill may now be finally finished by grinding or otherwise.

Figs. IV, V, and VI of said drawing represent a straight-fluted drill with a plurality of cutters and is composed, principally, of body 10 and cutters 11 and 12.

In carrying out our invention, we prefer to construct body 10 of material similar to body 1 hereinbefore described and provide thereon a suitable shank 13. Flutes 14 and 15 are provided on body 10 either by cutting, or casting, or forging, similar to flutes 100 4. Body 10 has two deep flutes 14, a slit which connects said deep flutes and which is adapted to receive cutter 11. The faces 16 of flutes 14 may have any suitable contour, but should have as large a cross-sectional area as possible, so as to provide the necessary chip-room. The leading faces 17 of flutes 14 are straight and adapted to receive cutter 11, similar to faces 9 hereinbefore described. The faces 18 of flutes 15 105 may have any suitable contour, but should have as large an area as possible to provide chip-room. The leading faces 19 of flutes 15 are straight and adapted to receive cutters 12. Cutter 11 is, in this instance, a flat strip 110 of suitable material, a little wider than the diameter of the finished drill, similar to cutter 2 hereinbefore described, and adapted to be molecularly united to the leading faces 17. Cutters 12 are flat strips of suitable material adapted to be molecularly united to the leading faces 19. We prefer to provide an undercut seat 21 (Fig. IV) for cutters 12 which seat aids to hold said cutters in place both during and after molecular union 120 with body 10.

The operations of hardening cutters 11 and 12 as well as the methods of forming body 10 and molecular union of said cutters to said body are similar to the corre- 130

sponding operations and methods hereinbefore described in connection with body 1 and cutter 2.

Final finishing of this drill is similar to 5 the twist-drill hereinbefore described.

For smaller drills we prefer to provide one cutter only (Figs. I and II) which extends centrally across the diameter of the body, has two cutting-faces, and determines 10 the size of the drill. For larger drills we prefer to provide a plurality of cutters, as for instance Figs. V and VI, so that material may be removed more rapidly, or in other words, a drill with a plurality of cutters 15 will do more work in a given time than a drill with one cutter. Providing more than one cutter on small drills is not practical mechanically. The cutters of these drills may extend along the entire length 20 of the fluted portion of the body as seen in Figs. I and IV, or part way along said fluted portion as for instance the cutter 20 of Fig. VII.

It is obvious that a twist-drill can be constructed with a plurality of cutters, a cross-section of which will appear as Figs. V or VI; or that a straight-fluted drill can be constructed with one cutter, a cross-section of which will appear as Fig. II. The drawing shows, for the purpose of clearly illustrating, a twist-drill with one cutter and a straight-fluted drill with four cutting-edges and three cutters, but we do not limit ourselves to such construction only.

35 It will be noted that we use a comparatively small amount of the higher-priced material in our drills, the body, being the larger part of the drill, is constructed of cheaper material, thus saving considerably 40 on cost of material.

A further advantage we have with our invention is that our drills do not break as easily as those constructed entirely of steel which is sufficiently hard for cutting purposes. The body of our drill, being constructed of soft and flexible material, strengthens and supports the cutter or cutters and renders the drill less liable to breakage. Our cutter or cutters, being of

uniform size throughout, have more flexibility than a drill which is constructed of one piece and which has a non-uniform cross-section.

Whereas this is an application for an article and descriptions of detail-steps as to 55 process of manufacture are unnecessary, and whereas many processes or methods may be employed to construct an article which embodies our invention, we have, hereinbefore, given a general outline only of several 60 methods of manufacture adapted to our invention. The outline of methods so described should, however, enable any one skilled in the art to construct an article which embodies our invention, either by the 65 methods as described, or by said methods with suitable modifications, or by other methods adapted to produce an article of our invention.

We claim:

1. A drill having a body, a shank on said body, two flutes in said body, a slit connecting said flutes, and a cutter in said slit and molecularly united to the leading faces of 70 said flutes.

2. A drill having a body, a shank on said body, a plurality of flutes in said body, a slit connecting two of said flutes, one cutter in said slit and molecularly united to the leading faces of said two flutes, and a plurality of cutters molecularly united to the 75 leading faces of the others of said flutes.

3. A drill having a body, a shank on said body, a plurality of flutes in said body, two of said flutes deeper than the others of said 80 flutes and connected by a slit, one cutter in said slit and molecularly united to the leading faces of said deeper flutes and extending across the diameter of said drill, and a plurality of narrower cutters molecularly 85 united to the leading faces of the others of said flutes.
